UNITED STATES PATENT OFFICE.

JOHN T. BRESNIN, OF LANCASTER, OHIO.

LENS GRINDING AND POLISHING MACHINE.

Application filed March 5, 1923. Serial No. 822,837.

To all whom it may concern:

Be it known that I, JOHN T. BRESNIN, a citizen of the United States, residing at Lancaster, in the county of Fairfield and State of Ohio, have invented certain new and useful Improvements in Lens Grinding and Polishing Machines, of which the following is a specification.

In carrying out the present invention it is my purpose to provide a lens grinding and polishing machine whereby a plurality of lenses may be ground or polished simultaneously and in such manner as to eliminate burning or scratching of the lenses during the polishing or grinding operation.

It is also my purpose to provide a lens grinding or polishing machine whereby the lenses may be ground or polished quickly and accurately and at comparatively small expense, the machine being constructed in such manner that the lenses may be readily and quickly placed and held in position for grinding, and quickly removed from such position after the grinding or polishing operation, thereby eliminating the loss of time and the expense incident to grinding or polishing machines, as heretofore constructed.

Furthermore, I aim to provide a machine of the class described which will embrace the desired features of simplicity, efficiency and durability, which may be installed and maintained at minimum expense, which will embody comparatively few parts, and these so arranged and correlated as to reduce the possibility of derangement to a minimum, and wherein all of the parts will be readily accessible so that repairs or replacements may be made quickly and inexpensively.

Another object of my invention is the provision of a machine of the type described, wherein the lenses may be ground or polished in multiples so that when the machine is operated at full capacity the polishing or grinding of a plurality of lenses will cost no more than the polishing or grinding of a single lens.

A still further object of my invention is the provision of a machine of the character described whereby a plurality of lenses may be held in proper relation to a spherical grinding element, so that all of the lenses may be treated simultaneously.

With the above recited objects in view, and others of a similar nature, the invention resides in the construction, combination and

arrangement of parts set forth in and falling within the scope of the appended claims.

In the accompanying drawings:

Figure 1 is a view in side elevation of a lens grinding or polishing machine constructed in accordance with my invention.

Figure 2 is an enlarged fragmentary vertical sectional view through one of the machines showing the lens carriers and spherical polishing element.

Figure 3 is a fragmentary top plan view showing the adjustment for a lens carrier.

Figure 4 is a fragmentary longitudinal sectional view through the spherical element showing the hemispheres of which the same is composed.

Figure 5 is a sectional view on the line 5—5 of Figure 2.

Figure 6 is a plan view of a three-armed lens carrier support.

Figure 7 is a similar view of a four-armed lens carrier support.

Figures 8 and 9 are detailed views of the shifting means for a lens carrier.

Referring now to the drawings in detail, 1 designates a base frame composed of suitable material and of any desired formation. In the present instance I arrange at the ends of the base frame 1 on the upper surface 85 thereof transversely extending supporting blocks 2—2 and fastened to these blocks 2—2 and upstanding therefrom are supporting standards 3—3, respectively, appropriately fastened to the blocks 2. On the upper ends 90 of the standards 3—3, respectively, are supporting beams 4—4. These beams 4—4 project outwardly beyond the standards 3 and the outwardly projecting ends are arranged in a horizontal plane, while the inner ends 95 of the beams are inclined downwardly, as at 5, and connected to the lower ends of the inclined portions 5 of the beams is a hanger 6 that carries a bearing 7 in which is journaled a horizontal shaft 8. The ends of the shaft 100 8 terminate slightly beyond the respective ends of the bearings 7 and are equipped respectively with clutch collars 9—9. Adjacent to one end of the shaft 8 there is also fixed a pinion gear 10 that meshes with a driving gear 11 carried by a shaft journaled in suitable bearings 12 carried by the upper surface of the base frame 1. This driving gear 11 is suitably connected with a source of power, so that motion may be transmitted 105 through the pinion gear 10 to the shaft 8 in order to revolve the latter within the bear-

ing 7 and thereby rotate the clutch members 9. In axial alinement with the bearing 7 at either side thereof are bearings 13, and journaled in these bearings 13 are shafts 14 co-axial with each other and with the shaft 8. The inner ends of the shaft 14 have splined thereon clutch members 15 that co-operate respectively with the clutch members 9, so that the shafts 14 may be connected to 10 and disconnected from the shaft 8 independently of each other. In the present instance each slideable clutch member 15 is connected with a yoke 16 carried by one end of a lever 17 that is pivoted between its ends, as at 18, 15 to the lower end of the adjacent inclined portion 5 of the beam 4 and these levers 17 are connected through the medium of rods 19, respectively, with the lower extremities of clutch shifter levers 20 fulcrumed between 20 their ends upon the respective beams 4. Thus, in the manipulation of the clutch shifter levers 20 the clutches may be engaged and disengaged, in order to establish and break the driving connections between 25 the shaft 8 and the shafts 14.

The outer ends of the shafts 14 project beyond the respective ends of the base frame 1 and extend into troughs or receptacles 21, respectively, that are carried by brackets 30 22 adjacent to the ends of the base frame 1, as clearly shown in Figure 1 of the drawings. Each receptacle 21 is adapted to contain a quantity of powder or other substance for grinding purposes in a manner which 35 will presently appear.

In the present embodiment of my invention, the outer end of each shaft 14 is circumferentially reduced in diameter and mounted upon such end is a spherical grinding element 23 shown clearly in Figures 2 and 4 of the drawings. Each grinding element 23 is in the form of a sphere divided into hemispheres 24—24. The central portions of the hemispheres 24 that confront each other are formed with inwardly extending sleeves 25, and these sleeves 25 aline axially with each other and fit upon the circumferentially reduced portion of the corresponding shaft 14 and are secured to the 40 reduced portion of such shaft by a washer and set screw 26 that is threaded into the outer end of the shaft and cooperates with the shoulder formed between the normal diameter of the shaft and the reduced end portion thereof to effectively clamp the hemisphere in a spherical relation, as clearly 45 shown in Figure 4.

These spheres are disposed respectively within the troughs 21 and rotated therein upon the rotation of the shaft 14, as previously described.

In accordance with my invention the outer end of each beam 4 is formed with a vertical bore 27, as clearly shown in Figure 2 of the drawings, and mounted within this bore 27

is a vertical rod 28. This rod 28 is movable vertically within the bore 27 and may be held in the desired position by means of set screws 29 that are threaded through the beam and engage the rod 28. The lower end of each rod 28 is disposed above and in line with the diametrical center of the corresponding grinding sphere and fastened to the lower end of each rod 28 is a multiple arm lens carrier support 30 which may be three-armed, as shown in Figure 6 of the drawings, or four-armed, as indicated by 30^a, in Figure 7 of the drawings. On each arm of the lens carrier support is a lens carrier 31. In the present instance each lens carrier 31 comprises a casting 32 that fits over the outer end of the corresponding supporting arm and is bolted or riveted thereto, as at 33. The outer end of this casting is formed with an outwardly projecting lug 34 formed with a transverse bore 35 and having the inner face thereof formed with radial ribs 36, as clearly shown in Figure 8 of the drawings. Placed in face to face contact with the ribbed surface of the lug 34 is a lug 37 on a casting 38 and the face of the lug 37 that confronts the ribbed face of the lug 34 is formed with corresponding ribs 39, clearly shown in Figure 9 of the drawings. This lug 37 is also provided with a bore 40 that alines with the bore 35 in the lug 34 and through these alining bores is passed a set bolt 41 by means of which the lugs may be clamped or held firmly in the desired adjusted position.

The casting 38 that carries the lug 37 is in the form of a sleeve, as shown in Figure 9 of the drawings, and threaded on the upper end thereof is a cap 42 that is formed with an opening alining axially with the bore of the sleeve. Through the bore of the sleeve and the opening in the cap 42 is passed a rod 43 that is movable longitudinally within the sleeve-like casting 38 and is equipped above the cap with a cam actuator 44, by means of which the rod 43 may be elevated and lowered within the sleeve.

The rods 43 carried by the arms of the lens carrier support rotate from the spherical grinding element 23, clearly shown in Figure 2 of the drawings, and on the lower end of each rod 43 is a multiple-armed lens support 45, the arms of which are equipped respectively with lens work holders 46 in which the lenses to be ground are placed. These lens work holders 46 are each of such construction that the lenses to be ground or polished may be quickly clamped to the respective arms and removed therefrom. The lens carrying arms 45 on the lower end of each rod 43 are normally urged downwardly toward the spherical grinding element 43 by means of a coiled expansion spring 47 that encircles the rod 43 between the casting 38 and the arms 45, thus holding the lenses in the clamps 46 in contact with the grinding

sphere 23, so that in the operation of the latter the lenses will be properly ground or polished. By means of the cam lifters 44 the rods 43 may be elevated against the 5 action of the spring when it is desired to lift the lens carrying arms out of engagement with the sphere.

From the foregoing description, taken in connection with the accompanying drawings, it will be seen that I have provided a lens grinding and polishing machine by means of which a plurality of lenses may be ground or polished simultaneously, and wherein by the use of spherical grinding 15 elements the lenses may be properly treated and the grinding spheres likewise treated for grinding or polishing purposes.

While I have herein shown and described one preferred form of my invention by way 20 of illustration, I wish it to be understood that I do not limit or confine myself to the precise details of construction herein shown and delineated, as modifications and variations may be made within the scope of the 25 claims and without departing from the spirit of my invention.

Having thus described the invention, what is claimed as new, is:—

1. In a lens grinding and polishing machine, a supporting frame, a beam projecting 30 from the frame and having in its end a vertically extending opening, a bar extending

through said opening, means for adjustably supporting the bar in the opening, a lens carrier support on the lower end of the bar, 35 a lens carrier including a pair of pivoted members one fixed to the lens carrier support and the other provided with a bore, a rod slidable through the bore, lens holders at the end of said rod, and a spring associated with said rod for holding the lens in the work holders against a grinding element. 40

2. In a lens grinding and polishing machine, a supporting frame, a beam projecting 45 from the frame and having in its end a vertically extending opening, a bar extending through said opening, means for adjustably supporting the bar in the opening, a lens carrier support on the lower end of the bar, 50 a lens carrier including a pair of pivoted members, one fixed to the lens carrier support and the other provided with a bore, a rod slidable through the bore, lens holders at the end of said rod, a spring associated with said rod for holding the lens in the work holder against a grinding element, and 55 a cam actuator on the rod engageable against the lens carrier through which the rod is slidable upon the grinding element and operable to withdraw the lens holders from the 60 grinding elements.

In testimony whereof I affix my signature.

JOHN T. BRESNIN.
